Primary Examiner—T. Chase Nelson*Assistant Examiner*—Karen Acker(74) *Attorney, Agent, or Firm*—Greenberg Traurig, LLP(57) **CLAIM**

The ornamental design for a hinge for adjustable furniture, as shown and described.

DESCRIPTION

FIG. 1 is a top perspective view of a hinge for adjustable furniture showing my new design, with the hinge shown in an engaged position;

FIG. 2 is a top plan view thereof;

FIG. 3 is a bottom plan view thereof;

FIG. 4 is a right side elevational view thereof, the left side elevational view being a mirror image thereof;

FIG. 5 is a front elevational view thereof;

FIG. 6 is a rear elevational view thereof;

FIG. 7 is a top perspective view of the hinge shown in FIG. 1 in a disengaged position; and,

FIG. 8 is a right side elevational view of the hinge shown in FIG. 7, the left side elevational view being a mirror image thereof.
